UNITED STATES PATENT OFFICE

157,758

GIRDLE

Louis Handler, New York, N. Y.

Application May 25, 1949, Serial No. 2,872

Term of patent 3½ years

(Cl. D20—2)

To all whom it may concern:

Be it known that I, Louis Handler, a citizen of the United States of America, residing in New York, county of New York, and State of New York, have invented a new, original, and ornamental Design for a Girdle, of which the following is a specification, reference being had to the accompanying drawing, forming part thereof.

Fig. 1 is a front view of a girdle, showing my new design.

Fig. 2 is a rear view thereof.

Fig. 3 is a front view of the detachable crotch portion thereof, and

Fig. 4 is a rear view thereof.

I claim:

The ornamental design for a girdle, substantially as shown.

LOUIS HANDLER.
